POT COVER HOLDER HOOK OR THE LIKE

Ruth C. Schlachter, Wheaton, Ill.
(406 Lincoln, Downers Grove, Ill. 60515)

Filed Mar. 5, 1973, Ser. No. 337,905

Term of patent 3½ years

Int. Cl. D7—99; D8—08

U.S. Cl. D7—129

FIG. 1 is a front perspective view of the pot cover holder hook or the like showing my new design;

FIG. 2 is a top plan view of the pot cover holder hook or the like;

FIG. 3 is a side elevational view;

FIG. 4 is a bottom elevational view;

FIG. 5 is a rear end elevational view; and

FIG. 6 is a front end elevational view.

The characteristic feature of my design for a pot cover holder hook resides in the combination of a substantially straight shank portion terminating at a first end thereof in a curved, major loop portion of relatively large radius and on a first plane with the end thereof being curved toward said shank and terminating in a reverse-curve end of minimum radius. At its opposite end, the shank portion has a deflected portion, as best shown in FIG. 3, at a minor angle to the main shank and extending along a second plane substantially perpendicular to the plane of the major loop portion and terminates in a curved, secondary loop portion, of a radius substantially smaller than that of the major loop portion, the secondary loop

portion being aligned along said second plane and being, therefore, substantially perpendicular to the major loop portion and offset therefrom by the deflected portion of the shank.

I claim:

The ornamental design for pot cover holder hook or the like, as shown and described.
